UNITED STATES PATENT OFFICE

REGINALD LEE, OF WINDSOR, VICTORIA, AUSTRALIA

POSTAL ENVELOPE

Application filed April 3, 1928, Serial No. 267,031, and in Australia November 16, 1927.

This invention relates to the manufacture of envelopes used to contain correspondence and documents for safe keeping and has for its object to provide an envelope that can be 5 more securely sealed.

According to the invention, the lower flap of an envelope is so adapted that instead of sealing the upper or sealing flap over it, as is at present the practise, the upper flap 10 is sealed over only a part of the lower flap which latter is then in turn sealed over the tip of the upper or sealing flap. By so doing both the upper and lower flaps of an envelope will be interlocked and doubly sealed 15 thus rendering it more difficult to interfere with either flap after sealing.

The invention is illustrated in the accompanying drawings, in which

Fig. 1 shows an envelope in perspective 20 view with the sealing flap open,

Fig. 2 is a detail in which the lower flap is in its ordinary position but provided with incisions parallel with the sealing edges, and

Fig. 3 is an elevation of an envelope closed 25 or sealed in accordance with this invention.

In this preferred form, the body 4 of the envelope is made as usual with side members 5, a lower flap 6 and a sealing flap 7, the side members being retained in position, when 30 folded over the body by the part 6.

In the apex of the flap 6 an incision is made to provide a tongue 8 that is exposed when the apex is bent backwards. This tongue is gummed to the side members in the usual way 35 while the apex, also gummed, is bent backwards as in Fig. 1.

The flap 7, when brought over for sealing is secured to the side members 5 and the tongue 8 and when this has been effected the 40 apex on 6 is turned over the tip of 7 and sealed thereto, as in Fig. 3, thus doubly sealing the envelope and its contents.

By making the incision in the lower flap 6 in the manner shown and described to provide the tongue 8 there need not be any additional paper used in making the envelope which in all main respects will resemble the ordinary envelope of commerce, save that through the incision the tip of the sealing flap 7 will be visible after sealing.

Thus, by means of this invention the upper and lower flaps of an envelope are interlocked and the envelope sealed in a twofold way thereby giving to the sealed article an extra security against interference by unauthorized persons. 55

Having now described my invention what I claim as new and desire to secure by Letters Patent is:

1. In a postal envelope, a sealing flap and a lower flap completing, with side members, the envelope body, a gummed strap formed in the lower flap near its apex and capable of hinging on said flap while the sealing flap is gummed to the main body, the sealing flap 60 being sealed at the same time to the lower flap and the hinged strap afterwards sealed over the tip of the main flap. 65

2. In a postal envelope, a body part, side members thereon, an upper or sealing flap, a lower flap, an inverted V shaped incision near the apex of the lower flap said incision extending downwards to a line just below the apex of the sealing flap when sealed to the body, a gummed strap formed in the lower 70 flap by the incision and hinging on the envelope said strap being capable of being brought over and sealed upon the main flap after sealing the envelope. 75

3. A postal envelope comprising, in combination with the usual front, end flaps, and closure flap, a lower back flap marginally, adhesively united to the lower marginal portions of the end flaps, except at its tip portion, the said tip portion having a V-shaped incision providing a V-shaped portion to underlie the tip portion of the closure flap when the said tip portion of the closure flap is in closing position in the sealing of the envelope, and a portion outwardly of the incision movable on a transverse fold line at the lower ends of the sides of the incision to permit disposal of the tip portion of the closure flap in closed position overlapping the outer side of the tip portion of the lower flap without insertion through the slit, the said tip portion of the closure flap and the marginal portions thereof bearing adhesive whereby to adapt the marginal portions to the sealed to the 80 85 90 95 100

upper marginal portions of the end flaps and the tip portion to be sealed to the outer side of the portion of the lower flap which is located within the bounds of the incision.

5 In testimony whereof I have signed my name to this specification.

REGINALD LEE.
